F. W. HOVEY, OF BOSTON, MASSACHUSETTS.

Letters Patent No. 60,781, dated January 1, 1867.

IMPROVEMENT IN LADDERS.

The Schedule referred to in these Letters Patent and making part of the same.

TO ALL WHOM IT MAY CONCERN:

Be it known that I, F. W. HOVEY, of Boston, in the county of Suffolk, and State of Massachusetts, have invented a new and useful Improvement in Ladders; and I do hereby declare that the following is a full, clear, and exact description thereof, which will enable others skilled in the art to make and use the same, reference being had to the accompanying drawing, forming a part of this specification, in which—

Figure 1 is a longitudinal central section of my improved ladder, and showing, in red lines, the position of the parts, when the vertical distance between the points connected by the ladder has been lessened.

Figure 2 is a front view of the lower part of the ladder, the middle part of the connecting-bar being broken away.

Figure 3 is a longitudinal central section of a ladder, illustrating a modification of my improvement.

Figure 4 is a detail sectional view of the lower part of a ladder, illustrating a modification of my improvement.

Figure 5 is a detail view of the slotted connection-bar.

Similar letters of reference indicate like parts.

My invention has for its object to furnish an improved ladder for use in situations where the inclination of the ladder may be varying constantly, or may be varied occasionally. And it consists in pivoting the steps of a ladder to its sides, and in combining with said pivoted steps the parts by means of which they are operated and regulated.

Figs. 1 and 2 represent a ladder, the upper end of which is designed to be pivoted in a fixed position, and its lower end to rest upon a floor, platform, or raft, the vertical distance between the supports for its two ends varying either occasionally or constantly. A are the sides of the ladder, the upper ends of which are pivoted to or hooked upon a support at the place for ascending to or descending from which the ladder is to be used. To the lower ends of the sides A of the ladder are pivoted wheels, B, upon which the ladder rests, and which roll along the floor, platform, or raft that supports them, as the distance between the supports for the upper and lower ends of said ladder varies. C are the steps of the ladder, the ends of which are pivoted to the sides A. These pivoting points may be pins attached to the ends of the steps, and working in the holes or sockets formed in the sides, A, of the ladder; or they may be the ends of the ordinary rounds of a ladder, to which the steps C may be permanently or removably attached, as shown in the drawings. The pivoting pins or points may be at or near the forward edge of the steps C, the rear edges of which are pivoted to the rod or bar D, by projecting ears, c¹, as shown in figs. 1 and 2. To the lower end of the bar D is pivoted a wheel, B, which rests upon the floor, platform, or raft upon which the lower end of the ladder stands, but its upper end is unsupported, except by being pivoted to the rear edges of the steps C. By this construction, however much the inclination of the ladder may change, the steps C will always be in a horizontal position, as shown in fig. 1. The steps C may be removably attached to the rounds of the ladder, by having hooks, c², or their equivalent, attached to the under side of the said steps, which said hooks pass around the rounds of the ladder, and are kept from displacement by pins, as shown in fig. 3. The pins by which the rear edges of the steps are pivoted to the bar D, are also removable, so that any number or all the steps C may be removed when desired. The ladder represented in fig. 3 is for use where the vertical distance between the upper and lower supports does not vary, and the position of the steps requires to be shifted only as the inclination of the ladder is changed. In this case, the wheels B are not required, and the bar D is supported and its position shifted by means of the notched arm E, the notches of which fit upon one of the lower rounds of the ladder, or upon some other support prepared for their reception. The upper end of the arm E may be pivoted to the lower end of the bar D, or at the rear edge of one of the steps C, as may be desired or convenient; or the upper end of the said arm, F, may be pivoted to a downwardly projecting part or angle of the ear, c¹, if desired. This improvement is especially designed for attachment to ship ladders, to boat and bath-house ladders, &c., but it is equally attachable to step and all other kinds of ladders. The notched bar or connecting-rod, E, may be replaced by a slotted bar or rod, F, the upper end of which is pivoted to the bar D, ear c¹, or step C, in the manner hereinbefore described. The lower part of the bar or rod F is slotted and passes over a round of the ladder, or over some other suitable support prepared for it, as shown in fig. 4, and it is held in place by a U-shaped pin, f, passing through holes in the bar F, in such a

way that one arm of said pin may be on each side of the round of the ladder, or other support, to which the said bar is attached. Numerous holes are made through the bar F for the reception of the pin f, so that the position of the steps C may be adjusted at pleasure. This construction I prefer, as it holds the steps C from movement in either direction.

Having thus described my invention, I claim as new, and desire to secure by Letters Patent—

1. The combination of the bar D and pivoted steps C, wheels B, and sides A of the ladder with each other, substantially as herein shown and described.
2. The combination of the notched arm E with the steps C and bar D of the ladder, substantially as herein shown and described.
3. The combination of the bar D and the removable pivoted steps C with the rounds and sides of the ladder, substantially as herein shown and described.
4. The combination of the slotted bar F and pin f with the bar D and steps C of the ladder, substantially as herein shown and described.

F. W. HOVEY.
